[57] CLAIM

The ornamental design for a magnetic hand tool for handling metallic canning lids, rings and the like, as shown and described.

DESCRIPTION

FIG. 1 is a front or rear elevational view of a magnetic hand tool for handling metallic canning lids, rings and the like showing my new design;

FIG. 2 is a right or left side elevational view thereof;

FIG. 3 is a top plan view thereof;

FIG. 4 is a bottom plan view thereof;

FIG. 5 is a sectional view taken along line V—V in FIG. 2; and

FIG. 6 is a fragmentary sectional view taken along line VI—VI in FIG. 1.

FIG. 1

FIG. 2

FIG. 6
